GAS-FILLED DISCHARGE TUBE

Johannes Gijsbertus Wilhelm Mulder, Eindhoven,
Netherlands, assignor to N. V. Philips' Gloei-
lampenfabrieken, Eindhoven, Netherlands

Application December 23, 1931, Serial No. 582,825
In Germany January 26, 1931

7 Claims. (Cl. 250—27.5)

This invention relates to a discharge tube comprising one or more anodes and an incandescent cathode, preferably an oxide cathode, as the source of electrons. The filling of the discharge tube consists partly or wholly of a vapour, for example mercury vapour, or of a mixture of vapours with or without the addition of one or more gases.

Discharge tubes of this kind are very frequently used for rectifying alternating current, although they are also used for other purposes.

The invention has for its object to increase the life of the incandescent cathode of discharge tubes designed for more than 10,000 volts and more than 10 amperes. In discharge tubes operating on such high voltages the life of the incandescent cathode is materially shorter than in the case of low-voltage tubes of the same type. This is due to the fact that in high-voltage tubes a very low vapor pressure is required to prevent undesired discharges, and this low pressure is largely responsible for the disintegration of the cathode.

The discharge tube according to the invention is characterized by the feature that the discharge between the anode and the cathode passes through one or more chambers for the condensation of the vapour. This permits maintaining in the cathode chamber a comparatively high pressure, which avoids excessive disintegration of the cathode, whereas the pressure in the anode chamber is kept very low as the vapour condenses before reaching this chamber. Although in the forms of construction hereinafter described only a single anode is shown, it is obvious that the same principles may be applied in the case of a plurality of anodes. In this case the discharge path to each anode may comprise an individual chamber or a plurality of individual condensing chambers, or again one or more condensing chambers common to all the discharge paths may be used.

In discharge tubes designed for the reception or amplification of signals which use a so-called gaseous cathode and in which small currents are controlled by a control grid, and which tubes are used to amplify signals, it has already been suggested to condense the vapor between the anode and the cathode. However, in this case the electrons for the main discharge are obtained from an auxiliary discharge, which is initiated in a vapor-filled chamber. In such case the condensation is to prevent ionization in the chamber in which the control grid is disposed, as other-

wise the control by means of the grid would be rendered impossible.

As stated above, according to the invention there is a condensation chamber for the metal vapour. The discharge tube consists consequently of alternate restricted and enlarged parts. It is well known that the ignition is rendered very difficult by the contractions of the tube wall. It is possible to overcome this difficulty by a suitable form of construction in which the wall of the discharge tube comprises one or more metal portions and in which a chamber, situated preferably between two successive metal wall portions of the discharge tube, is of sufficiently large cross-section to cause the vapour to condense in it. Although with the discharge tubes according to the invention artificial coolers for the condensing chamber may be important, they are superfluous in the form of construction described. Furthermore it is preferable for the discharge tube to be so shaped that the discharge path between the cathode and the anode forms one or more preferably acute angles. For this purpose the discharge tube may consist of a cathode chamber and of one or more condensation chambers arranged alongside the cathode chamber; in addition an anode chamber is provided above the last condensing chamber and the chambers are connected successively by insert tubes for the passage of the discharge. The bend in the discharge path makes it very difficult for the high-speed positive ion emanating from the anode chamber to reach the cathode so that the risk of disintegration of the incandescent cathode by impact of ions is decreased. Besides, these ions are slowed down in their travel by the increase in gas pressure which exists in the direction to the cathode. In addition, the bending of the discharge path is important because the difference in gas pressure between the various chambers is increased, because of the change in the direction of the flow of vapor.

The condensation chambers and the cathode chamber are preferably not only connected by the tubes for the discharge but also successively connected at their lower ends by return conduits for the condensate. These conduits are preferably provided with one or more bends to dampen the flow of the condensate therethrough. If the conduits were not provided with such bends, an increase in the vapor pressure within the cathode chamber would occur each time a drop of condensate falls to the bottom of the condensation chamber.

In another form of construction, the cathode

chamber, condensation chambers, and the anode chamber are arranged one above the other. In this case one or more hoods are provided to prevent the condensate flowing back to the cathode chamber, from coming into contact with the cathode.

Those portions of the discharge tube in which the condensate collects are preferably provided with contractions or re-entrant parts to secure a high level of the collecting condensate even with a small amount thereof.

In order that the invention may be clearly understood and readily carried into effect three forms of construction in accordance therewith will now be described more fully with reference to the accompanying drawings, in which

Figure 1 is a sectionized side view of a discharge tube in which the cathode chamber is arranged at the side of the condensation chamber,

Figure 2 is a sectionized side view of a discharge tube in which the various chambers are arranged one above the other, and

Figure 3 is a sectionized side view of a discharge tube in accordance with another embodiment of the invention.

Referring to Figure 1, a press 2 in the cathode chamber 1 supports an incandescent cathode 3. The cathode consists of a piece of rolled wire gauze 4 the successive convolutions of which are spaced apart at some intermediate distance, the coils of a heating helix being laid around the aggregate which is coated both internally and externally with a substance of high emissive power for instance with a suitable oxide coating. A cathode of this kind has a very high electron emission.

At the bottom of the cathode chamber 1 is a supply of mercury 5. The cathode chamber communicates through a tube 6 with the condensation chamber 7. The tube 6 consists of ferrochrome and is sealed on each side to the glass of the discharge tube. In addition, the chambers 1 and 7 are connected by means of a tube 8 to form a communicating vessel for the mercury.

The condensation chamber 7 communicates by means of a ferrochrome tube 9 with the anode chamber 10. The anode 11 is suitably supported, for example, by a ferrochrome plate 12 having its circumference sealed to the glass of the tube 6 and the leading-in conductor connected to the plate.

Due to the presence of the incandescent cathode 3 in the cathode chamber 1, the temperature and thus the vapor pressure of the mercury in this chamber is comparatively high. The mercury vapor which passes from the cathode chamber to the anode chamber 10 condenses, however, in the chamber 7. This chamber always remains comparatively cool as it is remote from the incandescent cathode and has a large surface which readily dissipates the heat to the surrounding air. The tube 8 enables the condensed mercury to flow back to the cathode chamber. A U-shaped portion 14 of the tube 8 dampens the flow of mercury so that fluctuating movements of the liquid and the variations in pressure incidental thereto are avoided. Consequently, a very low pressure prevails in the anode chamber so that the risk of flashing over is reduced to a minimum. Each of the chambers 1 and 7 comprises a re-entrant part 13 that constitutes a core. The mercury has consequently a high level while the amount of mercury is kept small. At the same time in spite of the small quantity of mer-

cury in chamber 1 a large area of mercury can be heated by the cathode 3.

The tubes 6 and 9 are provided with leads 20 and 21 respectively and may be connected to a suitable voltage which permits the starting potential to be considerably reduced. The voltage applied to these tubes generally falls between that of the anode and that of the cathode, and may be obtained, for example, from a separate secondary coil on the filament supply transformer.

In addition, by applying a direct voltage between the anode and the cathode and an alternating voltage to the tubes 6 and 9 it is possible to transform a direct current into an alternating current.

In Figure 2 like parts are designated by the same reference numerals as those used in Figure 1. The construction shown in Fig. 2 mainly differs from that in Figure 1 in that the discharge path has no bend, but the various chambers are arranged in axial alignment with each other. However should the mercury which condenses in the condensation chamber 7 and drips down, find its way to the incandescent cathode, this would cause a rapid deterioration at those points of the cathode on which mercury settles. To prevent this the ferrochrome tube 6 is provided with two internal and upward tapering tubes 15 and 16 made of the same metal. Thus, the mercury condensing in the chamber 1 is guided to flow between the tube 15 and the wall of the discharge tube and thence down along the wall of the tube 6 and along the exterior of the tube 16. The tube 16 forms a hood over the incandescent cathode so that dripping down of the mercury on the cathode is prevented.

In some instances, the tubes 15 and 16, having a high temperature, may cause the mercury drops coming into contact with them to volatilize. This has the drawback that it leads to sudden increases in pressure. In order to lessen this disadvantage, the tubes 15 and 16 may be instead of metal, for example of quartz. Or as shown in Figure 3, the condensed mercury may be returned to the chamber 1 through a circulating conduit 17. In such a construction a hood 18 may be useful in protecting the seal 19 from excessive heating. In addition, such a hood is adapted to improve the ignition. Similar services are also rendered by the hood 16 in Figure 2.

In some instances it is sufficient to have only one of the restricted wall portions of metal.

In addition to a vapour, one or more gases, preferably rare gases, may be enclosed within the tube.

Discharge tubes according to the invention can be constructed, for example, for voltages of 100 kilovolts and for discharge currents of 1 amp., and their life may be over 2000 hours. These values may be materially increased.

What I claim is:—

1. A discharge tube comprising a vapor filling, a large diameter glass bulb for serving as a condensation vessel, a second glass bulb containing a highly electron-emissive cathode and a quantity of the material of the filling in its non-vaporized state, a third glass bulb containing an anode and having a substantially smaller diameter than said first bulb, and two metal tubes having a diameter less than the diameter of said first bulb, each of said tubes connecting in a hermetical manner said first bulb to one of said latter two bulbs, the axes of said tubes forming an acute angle.

2. A discharge tube comprising a vapor filling,

a large diameter glass bulb serving as a condensation vessel, a second glass bulb containing a highly electron-emissive cathode and a quantity of the material of the filling in its liquid form, a 5 third glass bulb containing an anode and having a substantially smaller diameter than said first bulb, two metal tubes having a diameter less than the diameter of said first bulb, each of said tubes connecting in a hermetical manner said first 10 bulb to one of said two latter bulbs, the axis of said tubes forming an acute angle, and a return tube having a loop, said return tube being connected between the bottom portions of said first and second bulbs to allow the condensate to return 15 to said second bulb.

3. A discharge tube comprising an anode, and incandescent oxide cathode, a gaseous filling consisting partly of mercury vapor, an enclosure for the cathode, an enclosure for the anode, a condensation enclosure between said cathode and anode enclosures, a tube connecting said anode enclosure to said condensation enclosure, and a second tube connecting said cathode enclosure to said condensation enclosure, said tubes having 25 a smaller cross section than that of the condensation enclosure, the axes of said tubes forming an acute angle with each other.

4. A discharge tube comprising an anode, an incandescent oxide cathode, a filling consisting partly of vapor, an enclosure for said cathode, an enclosure for said anode, a condensation enclosure in axial alignment with said anode enclosure, and tubes individually connecting the condensation enclosure with the cathode and anode enclosures and having a smaller cross-section than the condensation enclosure, the axis of the tube connecting the condensation enclosure to the cathode enclosure forming an acute angle with the common axis of the anode enclosure and the condensation enclosure.

5. A rectifier tube having a cathode of high electron-emitting capacity, an anode, an enclosure for the anode, a condensation enclosure, an enclosure for the cathode, said anode and con-

densations enclosures being in axial alignment, said cathode enclosure being disposed laterally from said anode and condensation enclosures and spaced therefrom, a metal tube connecting the cathode enclosure to the condensation enclosure, 5 and a second metal tube connecting the anode enclosure to the condensation enclosure, said tubes having a smaller cross section than that of the condensation enclosure.

6. A rectifier tube for high voltages comprising 10 a high electron-emitting cathode, an anode, a filling consisting partly of vapor, an enclosure for the cathode, an enclosure for the anode, a condensation enclosure for the vapor and interposed between the cathode and anode enclosures, 15 metal tubes connecting said condensation enclosure to said cathode and anode enclosures and having a smaller cross-section than the condensation enclosure, the main discharge path between 20 said cathode and anode leading from said cathode enclosure through said condensation enclosure to said anode enclosure, and a tube having a U-shaped bend and connecting the bottom of said condensation enclosure to the bottom of said cathode enclosure for the return of condensate 25 to said cathode enclosure.

7. A discharge tube having a cathode, an anode, a filling comprising a vapor, an enclosure for the cathode, an enclosure for the anode, an enclosure intermediate between the anode and cathode enclosures for the condensation of said vapor, metal tubes connecting said condensation enclosure with the other enclosures and having a smaller cross-section than the condensation enclosure, the main discharge path between said cathode 35 and anode leading from said cathode enclosure through said condensation enclosure to said anode enclosure, and a tube for the return of the condensate to said cathode enclosure, said return tube being provided with a loop and connecting 40 the bottom part of said condensation enclosure to the bottom part of said cathode enclosure.
